UNITED STATES PATENT OFFICE.

FREDERICK E. BROWN, OF MCHENRY, NORTH DAKOTA.

CAR-SEAL.

1,077,587.

Specification of Letters Patent.

Patented Nov. 4, 1913.

Application filed April 22, 1912. Serial No. 692,414.

To all whom it may concern:

Be it known that I, FREDERICK E. BROWN, a citizen of the United States, residing at McHenry, in the county of Foster and State 5 of North Dakota, have invented certain new and useful Improvements in Car-Seals, of which the following is a specification.

This invention relates to seals, and more particularly to that class known as car seals. 10 An object of this invention is to improve and simplify devices of this character, rendering them comparatively simple and inexpensive to manufacture, reliable and efficient in use, and readily operated. 15 With the above and other objects in view, this invention resides in the novel features of construction, formations, combinations and arrangements of parts to be hereinafter more fully described, claimed and illustrated in the accompanying drawing, in which— 20

Figure 1 is a perspective view illustrating my invention; Fig. 2 is a longitudinal sectional view thereof; Fig. 3 is a plan view 25 of the blank from which one portion of the seal is formed, and Fig. 4 is a plan view of the blank from which the other portion of the seal is formed.

Referring to the drawings by characters of reference, the numeral 1 designates generally my improved seal, which consists of a band or strip 2, provided in one end with an aperture 3, and upon its opposite end with a substantially rectangular-shaped head 4, the opposite sides and outer end of which have located therein slots 5. A housing 6 is secured to the head 4, and has located upon its inner face an inwardly projecting spring 35 catch 7, adapted to engage the aperture 3 when that end of the strip is inserted within the housing at its rear end. The housing 6 is formed preferably of a substantially rec- 40

tangular-shaped blank, upon one end and the opposite sides of which are formed extensions 8. The side extensions 8 are provided with reduced extremities 9, which are adapted to be inserted through the side openings 5 formed in the head 4, with the shoulders 10 formed by this reduced extension contacting with the face of the head 4. The 50 reduced extensions, together with the extension formed upon the end of the blank, may be bent over, for the purpose of preventing the displacement of the housing from the before-mentioned head. The construction of 55 the side extensions of the blank serve to hold the top of the housing in spaced relation to the rectangular head 4.

From the foregoing disclosure it will be 60 obvious that a car seal is provided which will fulfil all of the necessary requirements of such a device.

Having thus fully described this invention, what I claim as new and desire to secure by Letters Patent is:

A car seal comprising a metallic strap provided with an aperture in one end thereof, the other end having a substantially rectangular-shaped head thereon, said head provided with elongated slots on the sides 65 and one end thereof, a housing of substantially rectangular shape secured to the head, said housing consisting of turned-down sides, tongues formed on the sides and one end 70 adapted to be received by said elongated slots, and an inwardly projecting resilient 75 catch located in said housing and adapted to be received by the aperture in said strap.

In testimony whereof I affix my signature in presence of two witnesses.

FREDERICK E. BROWN.

Witnesses:

G. P. CROSS,
LEWIS WALLEN.
